HANDLE OR THE LIKE

Frederic Buehner, Wilton, Conn., assignor to Buehner & Wanner, New York, N. Y., a copartnership

Application February 3, 1949, Serial No. 653

Term of patent 14 years

(Cl. D44—29)

To all whom it may concern:

Be it known that I, Frederic Buehner, a citizen of the United States of America, residing at Wilton, in the county of Fairfield and State of Connecticut, have invented a new, original, and ornamental Design for a Handle or the like, of which the following is a specification, reference being had to the accompanying drawing, forming part thereof.

In the drawing:

Fig. 1 is a front elevational view of a handle or the like, showing my new design.

Fig. 2 is a plan view of the same.

I claim:

The ornamental design for a handle or the like, substantially as shown.

FREDERIC BUEHNER.
